UNITED STATES PATENT OFFICE.

BEERI H. TUTTLE, OF ABSAROKEE, MONTANA.

HAYSTACKER.

Application filed May 11, 1922. Serial No. 560,232.

To all whom it may concern:

Be it known that I, BEERI H. TUTTLE, a citizen of the United States, and a resident of Absarokee, in the county of Carbon and State of Montana, have invented certain new and useful Improvements in Haystackers, of which the following is a specification.

My invention relates to hay stackers of the type embodying a base having a frame pivoted thereto for swinging movement from horizontal to vertical positions, whereby hay or other material deposited upon a fork carried by said pivoted frame may be elevated and stacked, and it is my purpose to improve hay stackers of this type by providing an adjustment for the fork whereby the hay may be thrown upon the top or to the far side of a stack or dropped at the rear side thereof without the necessity of changing the location of the stacker to the end that a maximum amount of hay may be handled and stacked in a minimum amount of time and by relatively small labor.

A further purpose of my invention is to provide a fork which is tilttable with respect to the pivoted frame by which it is carried and which is so connected with the stacker that when the pivoted frame approaches a substantially vertical position said fork is tilted to thereby assure the hay which is carried thereby being turned over and completely delivered therefrom onto the stack in an untangled condition. Furthermore, in this connection it is a purpose of my invention to provide a tilting arrangement for the fork which will cushion the latter when it is tilted to thereby relieve the stacker of strains due to sudden starting and stopping of its movable parts.

My inventive idea is capable of embodiment in various mechanical structures one of which is illustrated in the accompanying drawings, but it is to be understood that the structure shown is merely intended as a disclosure of the essential features and novel characteristics of my invention in a preferred form and that its scope is as defined in the appended claims.

In the drawings wherein like characters of reference denote corresponding parts in the different views—

Figure 1 is a perspective showing the normal relation of parts of my improved stacker;

Fig. 2, a longitudinal section through the

same showing the elevated position of the pivoted frame and the fork tilted;

Fig. 3, a fragmentary view similar to Fig. 2 showing the fork and related parts in the position they occupy during elevation of the pivoted frame and as the latter approaches a vertical position; and

Fig. 4, an enlarged perspective of one of the tilting arms for the fork.

Referring now to the drawings in detail, it will be observed that my improved stacker consists essentially of a base 10 and a frame 11 which latter is pivoted to the base for swinging movement from a normal horizontal position as shown in Fig. 1 to a vertical position as shown in Fig. 2, and vice-versa.

The base 10 is composed of a pair of beams 12, 12 secured together in parallel spaced relation by transverse beams 13 and 14 at or near the ends thereof respectively and braced by the diagonal bars 15, while the frame 11 is composed of a pair of parallel beams 16, 16 which are secured together in spaced relation near their free ends by a transverse beam 17 and which are pivoted at their other ends to the beams 12, 12 on the outside of the frame 10 as shown. The transverse beam 17 extends beyond the sides of the beams 16, 16 and has its ends connected to the latter beams by braces 18.

Pivoted inside of the base 10 to the beams 12, 12 near the transverse beam 13 are the lower ends of a pair of beams 19, 19 which are arranged in upwardly converging relation and at their free ends are secured together as at 20 where they have pivotal connection with a pair of downwardly diverging rods 21, 21 which are connected at their lower ends to the beams 16, 16 respectively next to the transverse beam 17. A pulley block 22 is secured to the transverse beam 14 of the base and an operating cable or rope 23 is trained over this pulley and connected to the upper end of the frame constituted by beams 19, 19.

Carried by the frame 11 at its free end is a fork 24 consisting essentially of two series of tangs 25 and 26 constituting what may be termed the bottom and rear of the fork respectively. The tangs 25 are secured together in parallel spaced relation by a pair of spaced, relatively light transverse beams 27 and 28 and are maintained thereby relatively and rigidly assembled, while the

- tangs 26 are also secured together in parallel spaced relation by an intermediately disposed, relatively light transverse beam 29 and at their inner ends are pivotally connected to the transverse beam 28 so that the bottom and back of the fork may be moved angularly with respect to each other as is apparent. Links 30 connect the free ends of the beams 16, 16 of frame 11 with the transverse beam 27 of the bottom of the fork whereby the latter at predetermined times is moved laterally with respect to and above the frame 11 as shown in Fig. 2 of the drawings.
- 15 One or more tilting arms 32, two being shown in the present instance, are pivoted intermediately to the transverse beam 17 of frame 11 and at one end are pivoted respectively to a pair of members 33 extending inward from the bottom of the fork, while at their other or free ends they are rounded and each has slidably mounted thereon a plate 34 which is normally maintained at its inward limit of movement by a coil spring 35 disposed between said plate and a head on the adjacent end of the arm. A cord or cable 36 of predetermined length connects said plates 34 with a portion of the base 10 such as the transverse beam 13.
- 20 30 Extending rearwardly from the back of the fork are two slotted plates 37 and pivoted to said plates and adjustable along the slots therein by means of bolts 37' are the forked ends of a pair of light beams 38 which at their opposite ends are pivotally connected to the respective beams 16, 16. By adjusting the first mentioned ends of said beams 37 in the slots of plates 36 the angular relation of the bottom and rear or back of the fork may be varied.
- 25 The normal relation of the parts described in the foregoing is shown in Figure 1 of the drawings in which position hay or other material to be handled or stacked is deposited on the fork in any suitable manner, after which a pull is exerted on the cable 23 either manually or otherwise to swing the frame 11 to a vertical or substantially vertical position as shown in Fig. 2 to elevate the fork and the hay carried thereby, it being apparent that a pull on cable 23 serves to swing the frame composed of beams 19, 19 downward and thereby exerts an upward pull on rods 21, 21 to elevate the frame 11.
- 30 35 Normally the bottom of the fork is so disposed that it constitutes in effect a continuation of the frame 11 and this relation of the fork and frame is maintained during the upward movement of the latter as shown in Fig. 3 until said frame reaches substantially the vertical position of Figure 2. However, as frame 11 in its upward movement approaches the vertical, cord 36 becomes taut and exerts a pull on the free ends of arms 32 which latter then swing about their intermediate pivots and serve to push the fork bodily outward or upward and also laterally with respect to the frame 11 with a quick, sharp movement tending to throw the hay from the fork, rearward or lateral movement being imparted to the fork by swinging movement of links 30 resulting from upward movement of the fork with respect to frame 11 as is manifest, while at the same time the free end of the rear or back of the fork is tilted downward due to the upward movement of the inner ends of tangs 26 with the bottom tangs 25 and to the fact that the outer ends of tangs 26 cannot move up with tangs 25 because of their connection through parts 37, 38 with the frame 11. If it is desired to drop hay from the fork at the near side of a stack an adjustment between parts 37, 38 is made by means of the slots in members 37 and the bolts 37' carried by members 38 so that the back of the fork will slope downward when the frame 11 is elevated, and if it is desired that the hay be thrown to the top or far side of a stack an adjustment is made as aforementioned so that the rear of the fork will be disposed horizontally or at an acute angle with respect to the tangs of the bottom of the fork, all as is apparent and is believed is well understood.
- 35 40 As the cord 36 becomes taut the plates 34 ride down the rounded ends of the arms 32 and compress the springs 35 thereby cushioning the tilting movement of the fork and as is apparent this cushioning of the fork and the manner of connecting the parts of the stacker serves to initiate return of the frame 11 to normal horizontal position following its elevation.
- 45 From the foregoing description taken in connection with the accompanying drawings, it is believed that the construction, operation and advantages of my improved stacker will be clearly understood and while I have herein shown and described one specific embodiment of my invention I do not confine myself to the detail arrangement shown as various modifications and changes may be made in and to the same within the scope of my invention as defined in the appended claims.
- 50 I claim:—
1. A stacker for hay and other materials including a base, a frame pivoted to said base for swinging movement, a fork comprising relatively pivoted bottom and rear portions, links pivotally connecting the frame with the bottom portion of said fork, and means for moving the fork longitudinally of the frame when the frame is swung with respect to the base whereby tilting movement is imparted to the fork by said links.
- 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950
2. A stacker for hay and other materials including a base, a frame pivoted to said base for swinging movement, a fork carried

by said frame, and connections between the frame and fork and between the fork and the base whereby the fork is moved bodily longitudinally and laterally with respect to the frame during swinging movement of the latter.

3. A stacker for hay and other materials comprising a base, a frame pivoted thereto for swinging movement, a fork comprising relatively pivoted bottom and rear portions, a link pivotally connected at one end to the frame and at its other end to the bottom portion of said fork, an arm pivoted intermediate to the frame and at one end to the bottom portion of said fork, and a flexible element of limited length connecting the other end of said arm with the base whereby a predetermined amount of swinging movement of the frame with respect to the base imparts rotation to said arm to move the fork longitudinally with respect to the frame and thereby cause the aforementioned link to move the fork laterally with respect to the frame.
- 25 4. A stacker for hay and other materials including a base, a frame pivoted thereto for

swinging movement, a fork, an arm pivoted to the frame and connected to said fork, an element connecting said arm to the base whereby swinging movement of the frame imparts tilting movement to the fork, and a yieldable connection between said element and said arm whereby tilting movement of the fork is cushioned.

5. A stacker for hay and other materials including a base, a frame pivoted thereto for swinging movement, a fork pivoted to said frame, an arm pivotally carried by the frame and connected to said fork, a member slidable on said arm, a spring normally urging said member in the direction of the pivotal connection of the latter with said frame, and an element connecting said slidable member to the base whereby swinging movement of the frame imparts rotation to said arm to tilt the fork relative to the frame, said member being adapted to slide on said arm and compress said spring during tilting movement of the fork to cushion the same.

In testimony whereof I hereunto affix my signature.

BEERI H. TUTTLE.
